CIRCUIT INTERRUPTING APPARATUS

Hugh A. Triplett, Wilmette, Ill., assignor to
Schweitzer-Conrad, Inc., Chicago, Ill., a corpora-
tion of Delaware

Application May 28, 1942, Serial No. 444,854

24 Claims. (Cl. 200—120)

My invention relates, generally, to circuit interrupting apparatus and it has particular relation to high voltage circuit interrupters in which the circuit opening is initiated by the blowing of one or more fusible elements.

An object of my invention is to provide for releasing an arc extinguishing fluid and for directing it into the arc space along a substantially straight and undeviating path.

Another object of my invention is to provide for lost motion between a reservoir containing a material which when released is an arc extinguishing medium and a tubular terminal through which the arc extinguishing fluid is released into the arc space in order to effect the release of the arc extinguishing fluid when the tubular terminal member has moved to a predetermined position.

A further object of my invention is to provide for hermetically sealing the reservoir to the tubular terminal member while still permitting relative movement therebetween to effect release of the arc extinguishing fluid.

It is also an object of my invention to provide an improved form of low temperature fusible element construction for a high amperage fuse.

Still another object of my invention is to provide a low resistance conducting path to the movable tubular terminal member of a circuit interrupter both before the terminal member moves to extend and extinguish the arc and while it is moving to the open circuit position.

A further object of my invention is to provide for cooling and condensing the products of the arc formed on operation of a circuit interrupter by passing the same through a restricted passageway one of the walls of which at least is formed of material which is capable of evolving an arc cooling medium due to the heat of the arc products.

A still further object of my invention is to provide for arresting the movement of the reservoir containing the arc extinguishing fluid and to permit the tubular terminal member to continue to move to effect release of the arc extinguishing fluid.

Other objects of my invention will, in part, be obvious and in part appear hereinafter.

For a more complete understanding of the nature and scope of my invention reference can be had to the following detailed description taken in connection with the accompanying drawings in which:

Figure 1 is a view, partly in section and partly in front elevation, showing one embodiment of my invention;

Figures 2 and 3 are top and side views of a piercing pin and support solder therefor arranged to be mounted at the end of the tubular terminal of the circuit interrupter shown in Figure 1.

for piercing the diaphragm of the reservoir or capsule containing the material which when released is an arc extinguishing fluid;

Figure 4 is a view, in side elevation, of the circuit interrupter shown in Figure 1;

Figures 5 and 6 are views, in side elevation, of the upper line terminal showing the movable stop in different positions;

Figure 7 is a top plan view of the movable stop and its support as shown in Figure 5;

Figures 8A and 8B, taken together, are a longitudinal sectional view of another embodiment of my invention; and

Figures 9A and 9B, taken together, are a longitudinal sectional view of still another embodiment of my invention.

Referring now particularly to Figures 1 and 4 of the drawings, it will be observed that the circuit interrupter construction there shown is similar to one of the embodiments of circuit interrupter construction disclosed in my copending application, Serial No. 224,696, filed August 13, 1938. The circuit interrupter here shown comprises upper and lower terminals 11 and 12 that are mounted on suitable insulators 13 and 14 which are carried by a suitable base member 15, such as a channel iron base. On the lower terminal 12 there is mounted a replaceable fuse cartridge shown generally at 16.

The replaceable fuse cartridge 16 comprises a housing 17 of suitable insulating material, such as a fiber lined "Bakelite" tube, having a terminal 18 at its lower end which is adapted to be secured to the lower terminal 12 by clamp means, shown generally at 20. At its upper end the insulating housing 17 is provided with a metallic ferrule 21 having an eye portion 22 integrally formed therewith for receiving a hook stick for placing the cartridge in operative position and for removing it therefrom.

Within the insulating housing 17 there is a liner of solid arc extinguishing material, such as magnesium borate or boric acid, in the form of rings 26 which are stacked one above the other 45 so as to provide a bore 27 therethrough. A tubular terminal member 28 is mounted for movement through the bore 27 and it is provided with a central longitudinally extending opening or passageway 29 for a purpose which will presently 50 be apparent. It will be observed that the tubular terminal member 28 is prevented from upward movement relative to the terminal member 18 by a strain wire 30. A fusible element 31, preferably in the form of a silver wire, interconnects the terminal member 18 and the tubular terminal member 28 to provide a calibrated fusible section.

Near its upper end the tubular terminal member 28 is threaded into a two-armed contact member 32 which is arranged to cooperate with

spring-biased contact fingers 33 that are carried by the upper terminal 11. During the normal operation of the circuit interrupter the principal portion of the current flowing between the terminals 11 and 12 flows through the contact fingers 33 and contact member 32 into the tubular terminal member 28.

It will be observed that a sleeve 37 is threaded onto the upper side of the contact member 32 and that this sleeve is provided with integrally formed oppositely extending arms 38 which interfit with suitably shaped slots in a yoke 39. The yoke 39 is provided with oppositely extending shafts 40 which are mounted in suitable bearings 41 carried by the upper terminal 11. Coil-springs 42, act between the shafts 40 and the bearings 41. By means of the coil springs 42 it will be observed that the tubular terminal member 28 is normally biased upwardly but that such movement is restrained by the strain wire 30. On flow of predetermined current in the circuit in which the circuit interrupter is connected the fusible element 31 will be fused. This will be followed by fusion of the strain element 30. Thereupon the tubular terminal member 28 will be restrained no longer but will be withdrawn through the bore 27 by the springs 42. The arc incident to the circuit interruption will be drawn between the lower end of the tubular terminal member 28 and the terminal member 18 at the lower end of the insulating housing 17.

The present invention is particularly directed to the provision of means for assisting in extinguishing relatively low current arcs between the terminal members 18 and 28 and also for scavenging the walls of the bore 27 after the arc has been interrupted so as to remove therefrom conducting particles and foreign material which might form a conducting path tending to facilitate subsequent breakdown or flashover. In order to effect this desired operation a reservoir or capsule 43 is mounted in the sleeve 37. The reservoir or capsule 43 contains a material, such as carbon dioxide, which, when released, forms an arc extinguishing fluid. A rupturable diaphragm 44 seals the reservoir or capsule 43. It will be understood that any suitable reservoir or capsule 43 can be employed such as the "Sparklet" type of capsule that is now on the market. It will be understood, however, that other types of reservoirs or capsules can be employed. The reservoir or capsule 43 is held in place by a coil compression spring 45. In order to seal the reservoir or capsule 43 to the tubular terminal member 28 and at the same time permit relative movement therebetween a flexible bellows 46 is provided, as shown, for enclosing the upper end of the reservoir or capsule 43. The flexible bellows 46 is secured, as by soldering, to the upper end of the sleeve 37.

In order to puncture the diaphragm 44 a pin or needle 47 is carried on a bridge 48, Figures 2 and 3, which is located at the upper end of the tubular terminal member 28. The pin or needle 47 may be any suitable sharp instrument such as a phonograph needle which will penetrate the diaphragm 44 and rupture the same.

It will be understood that, because of the coil compression spring 45, the reservoir or capsule 43 moves upwardly with the tubular terminal member 28 under the influence of the coil springs 42 after the strain element 30 has blown. After the tubular terminal member 28 has been moved upwardly through the bore 27 for a considerable distance, it is desirable to rupture the dia-

phragm 44 and release the arc extinguishing fluid. In order to accomplish this a stop 49 is mounted on a bracket 50, Figure 5, extending from the upper terminal 11 and is arranged, as shown, in the path of upward movement of the upper end of the flexible bellows 46. When the tubular terminal member 28 is moved upwardly sufficiently far to have the upper end of the flexible bellows 46 engage the stop 49, further upward movement of the reservoir or capsule 43 is prevented. However, because of the coil compression spring 45 and the flexible bellows 46, the tubular terminal member 28 continues to move upwardly a slight distance during which time the pin or needle 47 is caused to rupture the diaphragm 44. The arc extinguishing material within the reservoir or capsule 43 is then released and it flows directly through the passageway 29 into the arc space between the terminals 18 and 28. Since the arc extinguishing fluid is a non-conductor, it materially assists in extinguishing the arc, particularly low current arcs, by filling the arc space with a non-conducting medium, and, because of the blast action of the released arc extinguishing material, the conducting particles in the arc space are blown out of the lower end of the bore 27. In addition, after the arc has been extinguished the arc extinguishing fluid will continue to flow from the reservoir or capsule 43 through the passageway 29 under considerable pressure. This will scavenge the walls of the bore 27 and blow out conducting particles or carbon deposits which might tend to form a conducting path that would facilitate arcover or breakdown at a later time.

As indicated hereinbefore the two armed contact member 32 and the contact fingers 33 form the main conducting path between the tubular terminal member 28 and the upper terminal 11. Shortly after the tubular terminal member 28 begins to move upwardly, the contact member 32 disengages the spring contact fingers 33. All of the current is then transferred to the arms 38 and the yoke 39. With a view to providing a low resistance path between the yoke 39 and the upper terminal 11, a flexible conductor 51 interconnects the yoke 39 and one of the bearings 41. It will be understood that the flexible conductor 51 carries substantial current only during the circuit interrupting operation after the contact member 32 has disengaged the contact fingers 33.

After the circuit interruption has been completed, the tubular terminal member 28 is held in the upper position against the stop 49 by the coil springs 42.

In order to facilitate replacing the blown cartridge 18 it is desirable to provide means for removing the arms 38 from the yoke 39. For this purpose the stop 49 is pivoted at 52, Figure 5, on the bracket 50 and has a ring 53 integrally formed therewith into which the prong of a switch stick can be inserted for moving the stop 49 from the position shown in Figure 5 to that shown in Figure 6 of the drawings. Normally the stop 49 tends to swing downwardly under the influence of gravity and is held in the position shown in Figure 5 of the drawings by an ear 54 which engages the central flange portion 55 of the bracket 50.

When the stop 49 is moved to the alternate position as shown in Figure 6 of the drawings, the yoke 39 is permitted to move upwardly until the stops 56 integrally formed therewith engage the undersides of the bearings 41.

The prong of the hook stick then can be inserted in the eye 22 and, after the clamp 20 has been released, the blown cartridge 16 can be removed and replaced with an unblown cartridge.

It will be understood that the positions of the stops 58 are such relative to the bearings 41 that, before the stop 48 is moved from the position shown in Figure 5 of the drawings, and the cartridge 16 has blown, they are spaced a slight distance from the underside of the bearings 41. This insures that the pin or needle 47 can be moved through the full stroke to rupture the diaphragm 44. The upward thrust of the springs 42 is arrested solely by the stop 48 in the first instance. After the stop 48 is moved to the alternate position shown in Figure 6 of the drawings, the yoke 38 then moves upwardly slightly under the influence of the springs 42 until the stops 58 engage the undersides of the bearings 41.

It will be understood that, as soon as the prong of the switch stick is removed from the eye ring 58, the stop 48 will immediately swing downwardly under the influence of gravity. There is then no likelihood that the operator will forget to replace the stop 48 since it is automatically restored to its operative position. While the stop 48 will engage one side of the flexible bellows 46 in the released position, this does not interfere with the removal of the cartridge 16.

The clamp 20 can be of any suitable type. The construction shown is described in more detail in Patent No. 2,147,316, of Allan Ramsey. It includes a clamp arm 68 having an integrally formed socket portion 81 for receiving the prong of a switch stick. The clamp 20 while providing a low resistance conducting path between the terminal member 18 and the lower terminal 12 still permits a slight oscillation of the cartridge 16 as is required by the swinging yoke 38 in moving from one position to another during the circuit interrupting operation.

With a view to facilitating the positioning of the cartridge 16 in operative position the terminal member 18 is provided with oppositely extending arms 82 which are arranged to interfit with suitable recesses in arms 83 extending from the lower terminal 12. By this means the position of the cartridge 16 can be accurately determined.

In Figures 8A and 8B of the drawings there is shown a circuit interrupter construction in which several novel features are incorporated. The circuit interrupter is indicated, generally, by the reference character 70 and is so designed and constructed that it can be placed in and removed from standard fuse clips mounted on suitable line terminals. The circuit interrupter 70 is intended to be removed as a unit and replaced by a new or rebuilt cartridge of the same type and character.

It will be observed that the circuit interrupter 70 comprises terminals 71 and 72 which may be formed of copper tubing and which are adapted to be located in the respective fuse clips. Metallic fittings 73 and 74 are threaded into the ends of the tubular terminals 71 and 72, as shown. The fittings 73 and 74 are interconnected by an insulating sleeve 75 of fiber or similar material, the fittings 73 and 74 being threaded into the ends of the insulating sleeve 75 as illustrated. Surrounding the sleeve 75 is another sleeve 76 of insulating material. The sleeve 76 may be formed of a phenolic condensation product such as "Bakelite." A sleeve 77 of suitable insulating material such as glass or porcelain surrounds the sleeve 76 and provides a weatherproof covering having high dielectric characteristics. Gaskets 78 at the

ends of the outer sleeve 77 are provided to make a weathertight connection with the fittings 73 and 74.

Within the inner sleeve 75 there is provided a body of solid arc extinguishing material in the form of rings 79 of magnesium borate or boric acid. The rings 79 are stacked one above the other in alignment to provide a bore 80 through which a tubular terminal member 81 is arranged to be retracted for the purpose of extending and extinguishing an arc therein. The tubular terminal member 81 is provided with a centrally located passageway 82 for the purpose of conducting an arc extinguishing fluid into the arc space from a suitable reservoir for assisting in extinguishing the arc as will be described more in detail hereinafter. At the lower end of the tubular terminal member 81 the centrally located passageway 82 branches off into angularly directed openings or apertures 83 which, in combination with an opening 83' in a terminal fitting 86, direct the arc extinguishing fluid both along the walls of the bore 80 and over the fitting 86 and facilitate scavenging of the surfaces thereof.

The tubular terminal member 81 is held in place by a strain element 84 one end of which is secured over a pin 85 extending transversely through the lower end of the tubular terminal member 81. It will be noted that the transverse pin 85 is located at the top of the terminal fitting 86 which is threaded into the lower end of the tubular terminal member 81. The lower end of the strain element 84 is secured over a pin 87 which extends transversely through a terminal fitting 88 that is held by a nut 89 in place on a metallic spider 90. The spider 90 is secured by means of screws 91 to the fitting 74 to which the lower terminal tube 72 is connected as previously described.

The terminal fittings 86 and 88 are interconnected by a plurality of fusible elements 92. It will be observed that the fusible elements 92 are bowed inwardly intermediate their ends in order to provide the required length for the required time current characteristics with given spacing between the terminal fittings 86 and 88. The fusible elements 92 are located symmetrically in the terminal fittings 86 and 88 about the centrally located strain element 84.

Preferably the fusible elements 92 each comprise an outer sleeve of high melting point metal such as silver and a core of low melting point metal such as tin. The details of construction of such a fusible element are set forth in my Patent No. 2,243,135, and Patent No. 2,243,107, of Sigurd I. Lindell. The combination of a silver sheath and a tin core provides a high conductivity fusible element which operates at a relatively low temperature. Such a fusible element is particularly desirable in fuses the normal current carrying capacity of which is of the order of 400 to 600 amperes.

It will be observed that the metallic spider 90 is provided with apertures 96 therein. These apertures are provided to permit the free escape of the products of the arc formed between the terminal fittings 86 and 88 when the strain and fusible elements 84 and 92 have blown. The products of the arc comprise incandescent gases and metallic particles as well as arc extinguishing fluid such as water vapor evolved from the walls of the bore 80. It is desirable to cool and condense these products of the arc before they are permitted to escape to the atmosphere so as to reduce the fire hazard to a minimum and prevent arcing over to other energized conduc-

tors. For this purpose the products of the arc are caused to flow through a relatively narrow passageway 97 between the inner surface of the terminal sleeve 72 and the outer surface of a body of solid arc extinguishing material, such as magnesium borate or boric acid, formed by a stack of rings 98 of this material. These rings 98 are centrally located on a suitable stud 99 and are held in place by a nut 100 at the upper end as shown. The stud 99 is threaded into a closure member 101 which in turn is threaded into the lower end of the terminal sleeve 72. Apertures 102 in the closure member 101 serve to vent the passageway 97 to the atmosphere. The use of solid arc extinguishing material such as boric acid or magnesium borate for cooling and condensing the products of the arc provides a beneficial effect in that water vapor is evolved therefrom due to the heat of the products of the arc which tends to further cool and condense them and to suppress flames which might otherwise escape to the atmosphere.

At its upper end the tubular terminal member 81 is threaded into a metallic sleeve 106 which has an integrally formed radially extending flange 107. A coil compression spring 108 is strained between the underside of the flange 107 and the upper surface of the fitting 73 and acts to bias the tubular terminal member 81 upwardly. It will be recalled that the strain element 84 interconnects the terminal fittings 86 and 88 and it will be understood that the upward movement of the tubular terminal member 81 is restrained as long as the strain element 84 remains intact. The provision of the strain element 84 relieves the fusible elements 92 of the application of any tension stress.

Since the circuit interrupter 70 is intended for use in circuits in which the normal current carrying capacity is relatively high, such as 400 to 600 amperes, it is desirable to provide a low resistance high conductivity path between the tubular terminal member 81 and the sleeve terminal 71. For this purpose the sleeve 106 is provided with an enlarged portion the outer surface 109 of which forms a contact surface adapted to have contact engagement with flexible main contact fingers 110 that are carried by the fitting 73 and extend upwardly from its upper surface as shown. The main contact fingers 110 are curved adjacent their upper ends for receiving a garter spring 111 which serves to bias the contact fingers 110 into intimate contact engagement with the contact surface 109.

While it is desirable to have intimate contact engagement between the main contact fingers 110 and the contact surface 109 prior to circuit interruption, it is also desirable to relieve the contact pressure incident to this contact engagement so that the tubular terminal member 81 can move upwardly freely and quickly to extend and interrupt the arc. For this purpose the sleeve 106 is provided with a reduced section 112 so that after the rod-like terminal member 81 is moved upwardly a short distance the upper ends of the main contact fingers 110 no longer engage the sleeve 106.

Now it is desirable that there be provided a relatively low resistance conducting path between the tubular terminal member 81 and the terminal sleeve 71 while the former is moving upwardly through the bore 80 to perform the circuit interrupting operation. In the past it has been customary to employ one or more flexible conductors to perform this function. In

the circuit interrupter shown in Figures 8A and 8B of the drawings I have dispensed with the conventional form of flexible conductor and have provided auxiliary contact fingers 113 which extend downwardly from a ring 113' that has a press fit with the fitting 73. The lower ends of the auxiliary contact fingers 113 are curved for receiving a garter spring 114 which acts to urge the contact fingers into good contact engagement with the outer surface of the tubular terminal member 81 as it moves upwardly through the bore 80. It will thus be seen that the main contact fingers 110 provide the normal current carrying path between the tubular terminal member 81 and the tube terminal 71. At the same time the auxiliary contact fingers 113 assist in this current carrying function. The auxiliary contact members 113 are not of sufficient size and number to efficiently perform this function alone. However, the auxiliary contact members 113 have sufficient current carrying capacity to carry the fault current during the relatively short interval such as a few cycles while the tubular terminal member 81 is moving upwardly through the bore 80 and the arc incident to the circuit interruption is being extinguished.

With a view to assisting in extinguishing low current arcs and to scavenging the walls of the bore 80 after the arc has been extinguished a reservoir or capsule 117 is provided in the upper end of the sleeve 106 as shown. The reservoir or capsule 117 may be of the "Sparklet" type and is arranged to contain a material, such as carbon dioxide, which when released forms an arc extinguishing fluid and flows through the passageway 82 and apertures 83 into the bore 80 and arc space. The reservoir or capsule 117 is provided with a frangible diaphragm 118 which can be punctured for releasing the contents. A coil compression spring 119 reacts between the lower end of the reservoir or capsule 117 and the upper surface of a spider 120 located between the tubular terminal member 81 and the sleeve 106 for maintaining the reservoir or capsule 117 in spaced relation with respect to a pin or needle 121 carried by the spider 120. The reservoir or capsule 117 is hermetically sealed in place by a flexible bellows 122 which, while permitting relative movement between the reservoir or capsule 117 and the tubular terminal member 81 prevents the escape of arc extinguishing fluid in any direction except through the passageway 82.

When the strain and fusible elements 84 and 92 are blown, the coil compression spring 108 moves the tubular terminal member 81 upwardly through the bore 80 and an arc is drawn between the terminal fittings 86 and 88. Because of the coil compression spring 119, the reservoir or capsule 117 moves upwardly with the tubular terminal member 81 and in spaced relation thereto. Near the upper end of the stroke the upper surface of the flexible bellows 122 engages the under side of a disc 125 threaded onto a stem 126 which projects through a closure member 127 at the upper end of the tube terminal 71. A coil compression spring 128, which normally biases the disc 125 downwardly, is compressed and a cap 129 at the upper end of the stem 126 is raised. The raising of the cap 129 indicates that the circuit interrupter 70 has operated and that it should be renewed.

When no further upward movement of the disc 125 is permitted there is likewise no further

upward movement of the reservoir or capsule 177 permitted. However, the coil compression spring 168 continues to move the sleeve 166 and tubular terminal member 153 upwardly through a limited extent because of the provision of the coil compression spring 168 and the flexible bellows 122. The pin or needle 176 then pierces the diaphragm 178 and ruptures the same whereupon the contents of the reservoir or capsule 177 are released and the arc extinguishing fluid flows through the passageway 182 into the arc space where it performs the functions described hereinbefore.

Referring now particularly to Figures 9A and 9B of the drawings, it will be observed that the reference character 143, generally, designates a circuit interrupter which comprises an insulating housing 144 of glass or porcelain having a terminal 145 at its upper end and a terminal 146 at its lower end.

Within the insulating housing 144 there is a replaceable cartridge, indicated generally at 147. The cartridge 147 comprises a two layer sleeve 148 of insulation having a terminal 145 at its upper end arranged to have contact engagement with the terminal 146 at the upper end of the housing 144. At its lower end the insulating sleeve 148 has a terminal 150 in the form of a metallic sleeve which is arranged to be clamped to the lower terminal 146 on the housing 144. Within the insulating sleeve 148 there are rings 151 of arc extinguishing material, such as magnesium borate or boric acid, which are stacked one above the other and provide a bore 152 centrally thereof.

A tubular terminal member 153 is arranged to be movably mounted within the bore 152 and it is held in place therein, as shown, by a strain wire 154 which is supported by a cross-pin 155 carried by the terminal 149. A fusible element 156, preferably in the form of a silver wire, interconnects the terminal member 149 and the tubular terminal member 153 and forms the principal current carrying element therebetween and is arranged to be fused under certain predetermined overload or short circuit conditions as is readily understood. The tubular terminal member 153 is provided with a centrally located longitudinally extending aperture or passageway 157 through which an arc extinguishing medium is discharged to assist in arc extinction as will be presently described.

Referring now particularly to Figure 9B of the drawings, it will be observed that the tubular terminal member 153 is slidably mounted in a fitting 161. The fitting 161 is arranged to be biased downwardly to carry with it the tubular terminal member 153 by a coil compression spring 162 which reacts between the upper face of the fitting 161 and the underside of a fitting 163 threaded onto the lower end of the insulating sleeve 148. It will be observed that the sleeve-like lower terminal member 150 of the cartridge 147 is threaded onto the fitting 163 so as to make good electrical contact engagement therewith. Contact fingers 164 project downwardly from the fitting 163 and are arranged to have contact engagement with a cylindrical contact member 165 carried by and secured to the tubular terminal member 153. By means of the contact fingers 164 and contact member 165 the tubular terminal member 153 is directly connected through a relatively low resistance path to the lower terminal member 150 and thence to the lower line terminal 146.

With a view to interconnecting the tubular terminal member 153 and the fitting 163 after the contact member 165 has moved out of engagement with the contact fingers 164, a flexible conductor 166 is provided and connected, as shown, to the fitting 163 at the upper end and to the fitting 161 at the lower end. The flexible conductor 166 is coiled about the tubular terminal member 153 so as to provide sufficient length when the tubular terminal member 153 is moved downwardly to the open circuit position.

It will be observed that the fitting 161 is provided with a downwardly extending extension 170 through which the tubular terminal member 153 is relatively slidably. Chevron packing 171 serves to provide a fluid tight connection between the tubular terminal member 153 and the extension 170.

Threaded into the lower end of the extension 170 is a tubular connector 172 having a cap 173 threaded onto its lower end. The connector 172 and cap 173 cooperate to hold a reservoir or capsule 174 containing a material, such as carbon dioxide, which when released forms an arc extinguishing fluid. The reservoir or capsule 174 is closed or sealed by a diaphragm 175 which is arranged to be ruptured by a pin or needle 176 carried by a bridge member 177 at the lower end of the tubular terminal member 153. A coil compression spring 178 reacting between a nut 179 threaded onto the lower end of the tubular terminal member 153 and the upper side of a flange 180 integrally formed with the connector 172, serves to space the pin or needle 176 from the diaphragm 175 until certain predetermined conditions exist at which time the diaphragm 175 is ruptured and the arc extinguishing medium is discharged into the passageway 157.

In operation, when the fusible element 156 and strain wire 154 are blown, the tubular terminal member 153 is released to be moved downwardly under the influence of the coil compression spring 162. The cap 173 is moved downwardly and passes through a frangible diaphragm 181, such as mica or transparent plastic, and continues on outside of the tubular terminal member 153 to indicate that the device has operated. The fitting 161 and the attached sleeve 163 continue to move downwardly until the underside of the fitting 161 engages the upper edge of a stop ring 182 that is secured to the tubular terminal member 153 near its lower end. While further downward movement of the fitting 161 is prevented, because of the kinetic energy in the tubular terminal member 153, it continues to move downwardly through the fitting 161 and extension 170 until the pin or needle 176 carried by the bridge 177 at its lower end punctures the diaphragm 175. Further downward movement of the tubular terminal member 153 is then arrested.

The arc extinguishing fluid released from the reservoir or capsule 174 is then discharged through the passageway 157 and into the bore 152 in the solid arc extinguishing material 151. This arc extinguishing fluid assists in extinguishing the arc in the bore 152 between the terminal members 148 and 153 by sweeping out the vapors incident to the arc and detonizing the arc space so as to lessen the likelihood of the arc restriking on the next succeeding half cycle of the alternating current.

Since it is obvious that other embodiments of my invention can be made without departing from the spirit and scope thereof, it is intended

that all matter shown in the accompanying drawings and described hereinbefore shall be construed as illustrative and not in a limiting sense.

I claim as my invention:

1. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, and means for releasing said fluid when said tubular terminal member reaches a specified position to flow through said opening in said tubular terminal member and into the arc space for assisting in extinguishing an arc that may exist between said terminal members and for scavenging the walls of said bore.

2. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, said reservoir being mounted for movement with said tubular terminal member, and means for releasing said fluid when said tubular terminal member reaches a specified position to flow through said opening in said tubular terminal member and into the arc space for assisting in extinguishing an arc that may exist between said terminal members and for scavenging the walls of said bore.

3. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, means mounting said reservoir for movement with said tubular terminal member and permitting slight relative movement therebetween, and means for releasing said fluid as a result of said relative movement when said tubular terminal member is moved to a predetermined position to flow through said opening therein and into the arc space for assisting in extinguishing an arc that may exist between said terminal members and for scavenging the walls of said bore.

4. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material

which when released is in the form of an arc extinguishing fluid, means mounting said reservoir for movement with said tubular terminal member and permitting slight relative movement therebetween, a normally extended flexible bellows hermetically sealing said reservoir to said tubular terminal member, and means for collapsing said bellows and releasing said fluid as a result of said relative movement when said tubular terminal member is moved to a predetermined position to flow through said opening therein and into the arc space for assisting in extinguishing an arc that may exist between said terminal members and for scavenging the walls of said bore.

5. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, means mounting said reservoir endwise in alignment with said tubular terminal member for movement therewith and permitting slight relative movement therebetween, spring means biasing said reservoir away from said tubular terminal member, a normally extended flexible bellows hermetically sealing said reservoir to said tubular terminal member, and means for collapsing said bellows and overcoming the biasing force of said spring means and releasing said fluid as a result of said relative movement when said tubular terminal member is moved to a predetermined position to flow through said opening therein and into the arc space for assisting in extinguishing an arc that may exist between said terminal members and for scavenging the walls of said bore.

6. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, releasable means retaining said material in said reservoir, and means for releasing said releasable means when said tubular terminal member is in a specified position whereby said arc extinguishing fluid is released to flow through said opening in said tubular terminal member and into the arc space for assisting in extinguishing an arc that may exist between said terminal members and for scavenging the walls of said bore.

7. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc

extinguishing fluid, means mounting said reservoir for movement with said tubular terminal member, a rupturable diaphragm sealing said material in said reservoir, and means for rupturing said diaphragm when said tubular terminal member is moved to a predetermined position whereby said arc extinguishing fluid is released to flow through said opening in said tubular terminal member and into the arc space for assisting in extinguishing an arc that may exist between said terminal members and for scavenging the walls of said bore.

8. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, means mounting said reservoir for movement with said tubular terminal member and permitting slight relative movement therebetween, and means for rupturing said diaphragm as a result of said relative movement when said tubular terminal member is moved to a predetermined position whereby said arc extinguishing fluid is released to flow through said opening in said tubular terminal member and into the arc space for assisting in extinguishing an arc that may exist between said terminal members and for scavenging the walls of said bore.

9. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, means mounting said reservoir for movement with said tubular terminal member and permitting slight relative movement therebetween, a normally extended flexible bellows hermetically sealing said reservoir to said tubular terminal member, and means for collapsing said bellows and rupturing said diaphragm as a result of said relative movement when said tubular terminal member is moved to a predetermined position whereby said arc extinguishing fluid is released to flow through said opening in said tubular terminal member and into the arc space for assisting in extinguishing an arc that may exist between said terminal members and for scavenging the walls of said bore.

10. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, means mounting said reservoir endwise in alignment with said tubular

terminal member for movement therewith and permitting slight relative movement therebetween, a rupturable diaphragm sealing the end of said reservoir that is adjacent said tubular terminal member, spring means biasing said reservoir away from said tubular terminal member, a normally extended flexible bellows providing a hermetically sealed connection between said reservoir and said tubular terminal member, a needle carried by and movable with said tubular terminal member and directed toward said diaphragm, and stop means for arresting movement of said reservoir when said tubular terminal member is moved to a predetermined position whereupon said flexible bellows is collapsed, the biasing force of said spring means is overcome and said needle ruptures said diaphragm to release said arc extinguishing fluid to flow through said opening in said tubular terminal member and into the arc space for assisting in extinguishing an arc that may exist between said terminal members and for scavenging the walls of said bore.

11. In circuit interrupting apparatus, in combination, a body of arc extinguishing material having a bore, a pair of terminals between which an arc may be formed in said bore accompanied by the evolution of an arc extinguishing medium from the walls of said bore and discharge of flame and conducting particles, and means supplementary to said body of arc extinguishing material for cooling and condensing the products of the arc including means providing a restricted passageway at least one wall of which is provided by boric acid.

12. In circuit interrupting apparatus, in combination, a body of arc extinguishing material having a bore, a pair of terminals between which an arc may be formed in said bore accompanied by the evolution of an arc extinguishing medium from the walls of said bore and discharge of flame and conducting particles, and means supplementary to said body of arc extinguishing material for cooling and condensing the products of the arc including a body of boric acid over the outer surface of which said products are caused to flow, and an enclosure surrounding said body and providing therewith a restricted passageway to cause said products to come into intimate contact with said body.

13. In circuit interrupting apparatus, in combination, a pair of line terminal members disposed in insulated spaced relation, a pair of arc ing terminal members between which an arc may be drawn, one arcing terminal member being stationarily mounted and connected to one of said line terminal members and the other arcing terminal member being movable, and means for interconnecting said movable arcing terminal member and the other line terminal member including main contact finger means which carry the major portion of the current between said movable arcing terminal member and said other line terminal member before movement of the former is initiated, and auxiliary contact finger means arranged and adapted to carry the current between said movable arcing terminal member and said other arcing terminal member after separation of said main contact means.

14. In circuit interrupting apparatus, in combination, a pair of line terminal members disposed in insulated spaced relation, a pair of arc ing terminal members between which an arc may be drawn, one arcing terminal member being stationarily mounted and connected to one of

said line terminal members and the other arcing terminal member being movable and tubular in character, and means for interconnecting said tubular arcing terminal member and the other line terminal member including main contact means which carry the major portion of the current between said tubular terminal member and said other terminal member before movement of the former is initiated, and auxiliary contact means carried by said other terminal member and arranged and adapted to maintain contact engagement with the outer surface of said tubular terminal member as it moves away from said stationary arcing terminal member to extend the arc therebetween.

15. In circuit interrupting apparatus, in combination, a pair of line terminal members disposed in insulated spaced relation, a pair of arcing terminal members between which an arc may be drawn, one arcing terminal member being stationarily mounted and connected to one of said line terminal members and the other arcing terminal member being movable and tubular in character and having the end opposite the arcing end enlarged, a plurality of contact fingers carried by the other line terminal member and engaging said enlarged end portion of said tubular terminal, and a plurality of auxiliary contact fingers carried by said other line terminal member and adapted to engage the body of said tubular terminal member as it moves away from said stationary arcing terminal member to extend the arc therebetween.

16. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, said reservoir being movable together with said tubular terminal member, a lost motion connection between said reservoir and said tubular terminal member whereby relative movement therebetween is permitted, releasable means retaining said material in said reservoir, and means for releasing said releasable means in response to said relative movement between said reservoir and said tubular terminal member whereby said arc extinguishing fluid is released when said tubular terminal reaches a specified position to flow through said opening in said tubular terminal and into the arc space for assisting in extinguishing an arc that may exist between said terminal members and scavenging the walls of said bore.

17. In circuit interrupting apparatus, in combination a body of arc extinguishing material having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, said reservoir being movable together with said tubular terminal member, a lost motion connection between said reservoir and said tubular terminal member whereby relative

movement therebetween is permitted, said reservoir and said tubular terminal member being biased apart, means for arresting movement of said reservoir when it has been moved to a specified position while said tubular terminal member continues to move, releasable means retaining said material in said reservoir, and means for releasing said releasable means in response to said relative movement between said reservoir and said tubular terminal member whereby said arc extinguishing fluid is released when said tubular terminal reaches a specified position to flow through said opening in said tubular terminal and into the arc space for assisting in extinguishing an arc that may exist between said terminal members and scavenging the walls of said bore.

18. In circuit interrupting apparatus, in combination, a housing having a bore, a pair of relatively movable terminal members between which an arc may be formed, one of said terminal members being located at one end of said bore and the other being tubular and movable through said bore, said tubular terminal member having an opening extending longitudinally therethrough, operating means for moving said tubular terminal member through said bore, a reservoir for holding material which when released is in the form of an arc extinguishing fluid, rupturable means retaining said material in said reservoir, means mounting said reservoir for movement with said tubular terminal member and permitting slight relative movement therebetween, stop means for arresting movement of said reservoir when the same is moved with said tubular terminal member to a predetermined position while said tubular terminal member continues to move, means carried by said tubular terminal member adapted to pierce said rupturable means as a result of said continued movement of said tubular terminal member for releasing said arc extinguishing fluid to flow through said opening in said tubular terminal member and into the arc space, said stop means being manually movable away from its operating position to permit removal of said tubular terminal member, and additional stop means for said operating means for limiting movement thereof after the first mentioned stop means is moved away from its operating position to facilitate removal of said tubular terminal member.

19. In circuit interrupting apparatus, a body having a bore, a pair of relatively movable terminal members between which an arc is adapted to be formed, one of said terminal members being located adjacent one end of said bore and the other being tubular in character and movable through said bore, said tubular terminal member having an opening extending longitudinally therethrough, a reservoir for holding material which when released is in the form of an arc extinguishing fluid, said reservoir being mounted for movement with said tubular terminal member, and means for releasing said fluid when said tubular terminal member reaches a specified position to flow through said opening in said tubular member and into the arc space for assisting in extinguishing an arc that may exist between said terminal members and for scavenging the walls of said bore.

20. In circuit interrupting apparatus, a body having a bore, a pair of relatively movable terminal members between which an arc is adapted to be formed, one of said members being located adjacent one end of said bore and the other being tubular in character and movable through

said bore, said tubular terminal member having an opening extending longitudinally therethrough, a reservoir mounted on said tubular terminal member adjacent one end thereof for movement therewith and for relative movement therebetween, said reservoir being disposed to discharge into said tubular terminal member normally sealed and containing a material which when released is in the form of an arc extinguishing fluid, said tubular terminal member being open at its other end for discharge therethrough of said fluid, and means for releasing said fluid as a result of relative movement between said tubular terminal member and said reservoir.

21. In circuit interrupting apparatus, a body having a bore, a pair of relatively movable terminal members between which an arc is adapted to be formed, one of said members being located adjacent one end of said bore and the other being tubular in character and movable through said bore, said tubular terminal member having an opening extending longitudinally therethrough, a reservoir mounted on said tubular terminal member at one end thereof and yielding spaced therefrom with provision for relative movement of said tubular terminal member toward said reservoir, the latter being disposed in substantial alignment with said tubular terminal member to discharge into said one end thereof and being normally sealed and containing a material which when released is in the form of an arc extinguishing fluid, said tubular terminal member being open at its other end for discharge therethrough of said fluid, and means for releasing said fluid as a result of relative movement of said tubular terminal member toward said reservoir.

22. In arc extinguishing means for use in circuit interrupting apparatus, a tubular terminal member, a reservoir mounted on said member at one end thereof in substantial alignment therewith to discharge into said one end of said tubular member and for relative endwise movement

between said tubular terminal member and said reservoir, the latter being normally sealed and containing an arc extinguishing fluid under pressure, the other end of said tubular terminal member being open for discharge therethrough of said fluid, and means for releasing said fluid as a result of relative movement between said reservoir and said tubular terminal member.

23. In arc extinguishing means for use in circuit interrupting apparatus, a tubular terminal member, a reservoir mounted on said member at one end thereof in substantial alignment therewith to discharge into said one end of said tubular member and yielding held spaced therefrom for relative movement of said tubular terminal member toward said reservoir, the latter being normally sealed and containing an arc extinguishing fluid under pressure, the other end of said tubular member being open for discharge therethrough of said fluid, and means for releasing said fluid as a result of relative movement of said tubular terminal member toward said reservoir.

24. In circuit interrupting apparatus, in combination, a pair of line terminal members disposed in insulated spaced relation, a pair of arc-ing terminal members between which an arc may be drawn, one arcing terminal member being stationarily mounted and connected to one of said line terminal members and the other arcing terminal member being movable, and means for interconnecting said movable arcing terminal member and the other line terminal member including main contact means which carry the major portion of the current between said movable arcing terminal member and said other line terminal member before movement of the former is initiated and spring-biased auxiliary contact means arranged and adapted to carry the current between said movable arcing terminal member and said other arcing terminal member after separation of said main contact means.

HUGH A. TRIPPLETT.
